Primary Examiner — Messina L Smith*Assistant Examiner* — Carolyn W Davis(74) *Attorney, Agent, or Firm* — JEEN IP LAW, LLC(57) **CLAIM**

The ornamental design for a handheld fan, as shown and described.

DESCRIPTION

FIG. 1 is a front, right and top perspective view of a handheld fan, showing my new design;

FIG. 2 is a rear, left and bottom perspective view thereof;

FIG. 3 is a front view of FIG. 1;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view in the using configuration with a rope; and,

FIG. 10 is a perspective view in the folded configuration. The broken lines shown in the drawings illustrate portions of the handheld fan that form no part of the claimed design.

1 Claim, 10 Drawing Sheets(56)
